UNITED STATES PATENT OFFICE.

CARL BERTHOLD MANGELSDORFF, OF BERGEDORFF, GERMANY, ASSIGNOR TO
ALASTAIR M. FRAME, OF NEW YORK, N. Y.

TOY.

1,060,612.

Specification of Letters Patent.

Patented May 6, 1913.

Application filed October 23, 1911. Serial No. 656,302.

To all whom it may concern:

Be it known that I, CARL BERTHOLD MANGELSDORFF, a subject of the Emperor of Germany, and a resident of Bergedorff, Germany, have invented a certain new and useful Improvement in Toys, of which the following is a full, clear, and exact specification.

This invention relates more particularly to a class of spinning or humming tops which heretofore were made to rotate by a rapid unwinding of a string wound about the top or its handle before it is thrown, or dropped; or made to rotate by means of a 15 spring or whip.

My invention has for its object primarily to provide a toy wherein a top is adapted to be used in conjunction with a gun or toy-pistol from which it is shot so that it will 20 rotate rapidly and for a considerable length of time upon the ground or other suitable place, and which is designed to afford a great deal of pleasure and amusement especially to children in that practically no skill 25 or previous instruction is required in order to know the manner of manipulating the toy.

A further object of the invention is to provide a toy of simple, inexpensive and 30 efficient construction, and which is susceptible of being made so as to be very durable.

With these and other objects in view, the invention will be hereinafter more particularly described with reference to the accompanying drawing, which forms a part of this specification, and will then be pointed out in the claims at the end of the description.

In the drawing, Figure 1 is a side view, 40 partly in section and partly in detail, of one form of toy embodying my invention. Fig. 2 is a view of the top when dropped and spinning upon the ground. Fig. 3 is a section taken on the line II-II of Fig. 1, and Fig. 4 is a detail fragmentary view of a 45 form of clutch employed in the toy.

The toy embodying my invention comprises mainly a gun or toy-pistol 10 and a top, 50 as 11. The gun or pistol 10 has a barrel 12 and at one end thereof is a handle 13 whereby the gun may be conveniently carried and

manipulated by a person for spinning the top.

The end of the barrel 12 at the handle thereof is closed by a plate 14 midway of 55 which is an opening 15, and upon the exterior surface of the muzzle of said barrel is a rigidly held inner collar 15^a. Over the muzzle of the barrel 12 and over the collar 15^a is provided a winding element, or sleeve 60 16. The sleeve 16 is of sufficient length to extend some distance beyond the muzzle of the barrel 12, and also extends upon said barrel some distance below the collar 15^a whereby an annular groove 17 is provided 65 between the barrel and said sleeve. The sleeve 16 is rotatable upon the barrel 12, and in order to prevent its displacement from said barrel as well as serving as a guide while being rotated said sleeve is provided with a pin 18 having its free end disposed in the groove 17. Within the sleeve 16 is a disk or plate 19 which abuts against the end of the muzzle of the barrel 12, and centrally of said disk is an opening 20. 75

Projecting through and rigidly held in the opening 20 of the disk 19 is one end of a rod or shaft 21 whereby said rod will be revolved when the sleeve 16 is rotated, and the opposite end of the rod 21 is rotatable 80 in the opening 15 of the plate 14 at the opposite end of the barrel 12. Upon the end of the rod 21 extending beyond the disk 19 is fastened one end of a clutch or collar 22 having one edge thereof notched whereby a 85 plurality of teeth 23 are provided, and the other end of said collar abuts against the disk 19. Transversely of the teeth 23 of the collar 22 is provided a gripping member 24 consisting preferably of two spring rods 25 90 and 26 which are directed through two openings in said teeth and extend in parallel relation crosswise of said collar, as shown in Fig. 3. The spring rods 25 and 26 are spaced apart for a sufficient distance to permit the 95 plug to be inserted therebetween and held so that it may be easily released from its engagement.

Upon the rod or shaft 21 and in proximity to the plate 14 of the barrel 12 is a 100 ratchet or toothed wheel 27, and encircling said rod is a spiral spring 28. One end of

the spring 28 is fastened, as at 30, to the disk or plate 19 of the sleeve 16 or may be attached to the rod 21, and the other end of said spring is held to a pin 29 provided 5 within the barrel 12 in proximity to the ratchet wheel 27 so that when said spring is tensioned by rotation of the sleeve 16 the rod 21 will be wound for projecting the top 11, as will be hereinafter more fully de- 10 scribed.

Movably guided in a slot provided in the handle 13 of the gun is a trigger or lever 31 having one end pivoted, as at 32, to said handle, and the opposite end of which ex- 15 tends beyond the underside of the handle so as to be in the path of the finger of a person for operating or shooting the gun. The trigger 31 is adapted to normally engage the ratchet wheel 27, and for this purpose a 20 spring, as 33, is provided. The spring 33 is substantially U-shaped, and one of its ends is fastened within the handle 13 while its other end is in movable engagement with the underside of the trigger 31.

25 The top 11 which is used in conjunction with the gun 10 may be of any desired form, and has a spinning point or plug 34 which is of a diameter to fit snugly within the collar 22 upon the rod 21 of said gun. Upon 30 the plug 34 and some distance from its free end is provided a clutch or collar 35 one edge of which is notched or has a plurality of teeth 36 of a similar formation to the teeth 23 of the collar 22.

35 In operating the toy the rod 24 of the gun is wound simultaneously with the tensioning of the spiral spring 28 by rotation of the sleeve 16, as above described. The rod 21 will be held against reverse rotation by the 40 ratchet wheel 27, and the top 11 is then positioned so that the plug 34 may be inserted in the collar 22 of said rod whereby the plug will be yieldingly held between the spring rods 25 and 26 of the gripping member 24.

45 The teeth 36 of the collar 35 of the top and the teeth 23 of the collar 22 of the rod 21 of the gun will then be engaged for holding the top in the muzzle of the gun. In order to propel the top from the gun for spinning 50 upon a surface, as shown in Fig. 2, the trigger 31 is forced against the tension of the spring 33 to disengage it from the ratchet wheel 27. The tension of the spring 28 will then rapidly rotate the rod 21, and com- 55 municate its movement of rotation to the plug of the top which in turn will be released from the engagement with the spring rods 25 and 26 of the gripping member 24 and the top will be shot from the gun and 60 spun upon the ground.

In the foregoing description I have embodied the preferred form of my invention, but I do not wish to be understood as limiting myself thereto, as I am aware that modifications may be made therein without de-

parting from the principle or sacrificing any of the advantages of this invention, therefore I reserve to myself the right to make such changes as fairly fall within the scope thereof.

Having thus described my invention, I claim as new and desire to secure by Letters Patent:—

1. In a toy, in combination, a top having a plug, a pistol having a barrel and a handle, a rod rotatable within the barrel, a spring adapted to be tensioned when the rod is rotated, means connected to the rod whereby it may be rotated, means provided upon the rod and adapted to detachably hold the plug of the top when inserted in the muzzle of the barrel of the pistol, a trigger movably held to the handle of the pistol, and means provided upon the rod and adapted to be engaged by the trigger to hold said rod when rotated so that when the trigger is pulled for disengagement with the holding means the rod will be reversely rotated by said spring for imparting rotation to the top whereby its plug will be released and the top propelled from the pistol. 70 75 80 85 90

2. In a toy, in combination, a top having a plug, a pistol having a barrel and a handle, a rod rotatable within the barrel, a spring adapted to be tensioned when the rod is rotated, means connected to the rod whereby it may be rotated, a clutch provided upon the rod and adapted to detachably hold the plug of the top when inserted in the muzzle of the barrel of the pistol, a trigger movably held to the handle of the pistol, and means provided upon the rod and adapted to be engaged by the trigger to hold said rod when rotated so that when the trigger is pulled for disengagement with the holding means the rod will be reversely rotated by said spring for imparting rotation to the top whereby its plug will be released and the top propelled from the pistol. 95 100 105

3. In a toy, in combination, a top having a plug, a pistol having a barrel and a handle, a rod rotatable within the barrel, means connected to the rod whereby it may be rotated, a spring provided within the barrel and adapted to be tensioned when the rod is rotated, a clutch provided upon the rod and adapted to detachably hold the plug of the top when inserted in the muzzle of the barrel of the pistol, a trigger movably held to the handle of the pistol, and a ratchet provided upon the rod and adapted to be engaged by the trigger to hold said rod when rotated so that when the trigger is pulled for disengagement with the ratchet the rod will be reversely rotated by said spring for imparting rotation to the top whereby its plug will be released and the top propelled from the pistol. 110 115 120 125

4. In a toy, in combination, a top having a plug, a pistol having a barrel and a handle, 130

5 a rod rotatable within the barrel, a sleeve revolubly held upon the muzzle of the barrel and connected to the rod whereby said rod may be rotated when the sleeve is revolved, means provided upon the rod and adapted to detachably hold the plug of the top when inserted in the muzzle of the barrel of the pistol, a trigger movably held to the handle of the pistol, and means provided upon the rod and adapted to be engaged by the trigger to hold said rod when rotated so that when the trigger is pulled for disengagement with the holding means the rod will be reversely rotated by said 10 spring for imparting rotation to the top whereby its plug will be released and the top propelled from the pistol.

5. In a toy, in combination, a top having a plug, a clutch provided upon the plug, a pistol having a barrel and a handle, a spring adapted to be tensioned when the rod is rotated, a sleeve revolubly held upon the muzzle of the barrel and connected to the rod whereby said rod may be rotated when the sleeve is revolved, a clutch provided upon the rod and adapted to detachably engage the clutch of the top when the plug is inserted in the muzzle of the barrel of the pistol, a trigger movably held to the handle of the pistol, and means provided upon the rod and adapted to be engaged by the trigger to hold said rod when rotated so that when the trigger is pulled for disengagement with the holding means the rod will be reversely rotated by said spring for imparting rotation to the top whereby said plug will be released and the top propelled from the pistol.

6. In a toy, in combination, a top having a plug, a clutch provided upon the plug, a pistol having a barrel and a handle, a rod rotatable within the barrel, a spring arranged within the barrel and adapted to be tensioned when the rod is rotated, a sleeve revolubly held upon the barrel and connected to the rod whereby said rod may be rotated when the sleeve is revolved, means provided upon the rod and adapted to detachably engage the clutch of the top when the plug thereof is inserted in the muzzle of the barrel of the pistol, a trigger movably held to the handle of the pistol, and a ratchet wheel provided upon the rod and adapted to be engaged by the trigger to hold said rod when rotated so that when the trigger is pulled for disengagement with the ratchet wheel the rod will be reversely rotated by said spring for imparting rotation to the top whereby its plug will be released and the top propelled from the pistol.

7. In a toy, in combination, a top having a plug, a clutch provided upon the plug, a pistol having a barrel and a handle, a rod rotatable within the barrel, a spiral spring arranged around the rod and adapted

to be tensioned when the rod is rotated, means provided upon the barrel and adapted to rotate the rod, a clutch provided upon the rod and adapted to detachably engage the clutch of the top when the plug thereof is inserted in the muzzle of the barrel of the pistol, a trigger movably held to the handle of the pistol, and means provided upon the rod and adapted to be engaged by the trigger to hold said rod when rotated so that when the trigger is pulled for disengagement with the holding means the rod will be reversely rotated by said spring for imparting rotation to the top whereby its plug will be released and the top propelled from the pistol.

8. In a toy, in combination, a top having a plug, a pistol having a barrel and a handle, a rod rotatable within the barrel, a spiral spring arranged around the rod and adapted to be tensioned when the rod is rotated, a sleeve revolubly held upon the barrel and connected to the rod whereby said rod may be rotated when the sleeve is revolved, a collar held upon the end of the rod at the muzzle of the barrel, a yielding gripping element provided upon the collar and adapted to detachably engage the plug of the top when inserted in the muzzle of the barrel of the pistol, a trigger movably held to the handle of the pistol, and a ratchet wheel provided upon the rod and adapted to be engaged by the trigger to hold said rod when rotated so that when the trigger is pulled for disengagement with the ratchet wheel the rod will be reversely rotated by said spring for imparting rotation to the top whereby its plug will be released and the top propelled from the pistol.

9. In a toy, a pistol having a barrel and a handle, a rod rotatable in the barrel, a spring arranged within the barrel and adapted to be tensioned when the rod is rotated, means connected to the rod whereby it may be rotated, a collar having one end held upon the rod at the muzzle of the barrel, a plurality of teeth formed upon the opposite end of the collar, a yielding gripping element provided upon the collar, a trigger movably held to the handle of the pistol, and a ratchet wheel provided upon the rod and adapted to be engaged by the trigger to hold said rod when rotated so that when the trigger is pulled for disengagement with the ratchet wheel the rod will be reversely rotated by said spring.

10. In a toy, a pistol having a barrel and a handle, a rod rotatable in the barrel, a spiral spring arranged around the rod and adapted to be tensioned when the rod is rotated, a sleeve revolubly held upon the barrel at the muzzle thereof and connected to the rod for rotating said rod, a collar having one end held upon the rod at the muzzle of the barrel and having openings trans-

versely therethrough, two spring rods disposed through the openings of the collar, a plurality of teeth formed upon the opposite end of the collar, a trigger movably held to the handle of the pistol, and a ratchet wheel provided upon the rod and adapted to be engaged by the trigger to hold said rod when rotated so that when the trigger is pulled for disengagement with the

ratchet wheel the rod will be reversely rotated by said spring. 10

This specification signed and witnessed this second day of October A. D. 1911.
